BEAN SNIPPING MACHINE

Benjamin I. Buck, Baltimore, Md., assignor of
one-half to H. Beale Rollins, Baltimore, Md.

Application July 24, 1947, Serial No. 763,360

3 Claims. (Cl. 146—86)

1

This invention relates to a bean snipping machine, and more particularly pertains to such a machine wherein beans are introduced into perforated hollow cylinder tumblers, in a continuous stream and discharged therefrom in a continuous stream, the beans, during the tumbling action, having the ends thereof, which protrude through the perforations, snipped off by stationary knives located in shearing contact with the outer surface of the cylinder surfaces.

In old and well known types of perforated cylinder bean snipping machines, as described in my United States Patents 1,882,481 and 1,990,425, the batch method of bean snipping was employed, a batch of beans being placed in the perforated cylinders and tumbled therein until, by the laws of chance, all but a trifling percentage thereof had the ends trimmed therefrom, the time the tumbling consumed being a measure of the percentage of beans of the batch that had the ends trimmed therefrom. In this old type of batch treatment, the mechanism had to be stopped, while the beans were unloaded and loaded, requiring the services of stand-by workmen and accurate timing of the length of each of the tumbling operations.

By this invention, I provide a cylindrical tumbler bean snipping device which automatically, as set, depending upon the grade of beans being treated, continuously accepts beans and discharges them, without stopping of the machine and without requiring the services of stand-by operators, and during the time the beans are in the device the required percentage have the ends snipped off.

In general, I provide tumbling units, each comprising a plurality of perforated hollow cylinder sections secured end to end in axial alignment, with restricted opening partition means between the cylinder sections permitting travel of beans from one cylinder section to the next cylinder section, the beans finally issuing from the end of the last cylinder section of the unit. The unit is inclined with its rotational axis to the horizontal, with the receiving end higher than the discharge end, so that the beans are transferred from one end of the unit to the other by gravity, the transfer from cylinder to cylinder being accomplished by special means which I provide, for that purpose. I also provide a gate means gauging the delivery of beans to a unit, as delivered by a conveyor, to a stream of a size which assures that all the beans delivered to the unit, or at least all but one or two percent of them, have the ends snipped therefrom as they pass therethrough and are dis-

2

charged. I provide a conveyor bean delivery means at the receiving end of such unit, and in order to more effectively utilize such conveyor means I provide a number of snipping units in parallel, side by side, with gate means individual to each unit to gauge the share of beans continuously received thereby. The conveyor means is supplied by a common hopper into which a supply of beans is dumped from time to time.

Therefore, it is an object of this invention to provide a bean snipper of the perforated cylinder tumbling type which continuously snips the ends of beans delivered thereto in controlled numbers.

It is another object of the invention to provide such a machine wherein beans are transferred by special gravity transfer mechanism from section to section of a long multi-cylinder unit.

Another object of the invention is to provide such a machine in which the multi-cylinder unit rotates on an axis tilted to the horizontal so that beans are conveyed therethrough by gravity from the elevated receiving end to the lower delivery end.

Another object of the invention is to provide means for continuously supplying beans in a certain selected amount to such a machine unit or to a plurality of them in parallel arrangement.

With these and other objects in view which will become apparent in the following specification and claims, I describe my invention in connection with the drawings, in which:

Fig. 1 is a side elevation of the machine, with certain frame members broken away.

Fig. 2 is a section on line 2—2 of Fig. 1, showing the trimming knives for the first cylindrical section.

Fig. 3 is a top plan view of the substance of Fig. 1, with certain parts broken away to reveal the interior of certain of the cylindrical sections.

Fig. 4 is a section through the machine on the line 4—4 of Fig. 3.

Fig. 5 is an enlarged detail of the joint between two cylindrical sections, on the line 5—5 of Fig. 4, showing the flanged collar and transfer paddles.

Fig. 6 is a section on the line 6—6 of Fig. 3.

Fig. 7 is a sectional view on the line 7—7 of Fig. 1.

Fig. 8 is a vertical longitudinal section of the left end of the cylinder unit of Fig. 1.

Fig. 9 is a view similar to Fig. 5 showing the cylinder unit axis tilted and illustrating the transfer of beans from one section to the next.

Fig. 10 is an elevation of the left end of the cylinder unit of Fig. 1, on the line 10—10 of Fig. 8, showing the support and driving mechanism.

Fig. 11 is a detail of the support for the receiving end of the unit shown in Fig. 10.

Fig. 12 is a view of the top end of the tilt adjusting mechanism.

Fig. 13 is a section on the line 13—13 of Fig. 1.

Fig. 14 is a plan view of the conveyor system for supplying a plurality of units, continuously, with beans.

Fig. 15 is an elevation of the substance of Fig. 14.

In the drawings the same reference numbers are given to the same parts throughout the several views, and the sectional views are taken on the section lines looking in the direction of the arrows.

Framework and drive for the bean snipping unit

Referring to Figs. 1, 3, 7, 10, 11 and 13, I provide a supporting frame comprising leg pieces 20, 21, 22 and 23, upper longitudinal stretchers 24 and 25, corresponding lower longitudinal stretchers, of which one, 26, is shown in Fig. 1, and cross stretchers 27 and 28.

Within the frame is a tiltable cylinder unit support frame comprising longitudinal stretchers 29 and 30, joined by cross members, to be described, which support and act as bearings for the said cylinder unit. The mid-point of the tiltable support frame is connected by arcuate member 31 (Fig. 13) bolted to the under edges of stretchers 29 and 30. At the receiving end of the bean snipping unit, which is at the left in Figs. 1 and 3, the stretchers 29 and 30 are joined by arcuate cross support members 32 and 33 (see Fig. 11) bolted respectively to the upper and lower edges thereof. At the delivery end of the bean snipping unit, which is at the right in Figs. 1 and 3, the stretchers 29 and 30 are joined by arcuate cross member 34 (see Fig. 7) bolted to the under edges thereof. The several cross members have rollers mounted therein to support, for rotation, the cylinder unit to be described. The tilting frame, or cradle, thus constructed, has bolted, on the side of stretcher 30, a plate 35 (Figs. 1 and 3) from which extends a trunnion pin 36 which is held in a bearing 37 bolted to the top of stretcher 24 of the support frame. Referring to Fig. 3, stretcher 29 has a plate 38 secured to its outside, said plate having a hollow trunnion pin 39 extending outwardly to be held in bearing 40 bolted to the top of support frame stretcher 25 and extending inwardly through a hole 41 bored in stretcher 29, ending in a recess 42 cut on the inner side of said stretcher. It is apparent that the tilting frame, or cradle may be rocked on the horizontal axis passing through bearings 37 and 40. To adjust the structure so the delivery end of the cylindrical unit, to be described, held in the tilting frame, is lower than the receiving end, the bearings 37 and 40 have been displaced from the mid-point of the framework toward the receiving end, or left, as seen in Fig. 1, so the center of gravity of the framework is toward the delivery end, thus causing that end to be drawn down by gravity. To adjust the tilt to the proper degree to insure the proper progression of beans from the receiving end of the cylindrical unit to the delivery end thereof, by gravity, a rod 43 (see Figs. 1 and 12) depending from arcuate support member 34 has a ball 44 on its end, which is held in a socket 45 wobble-mounted in a screw bolt 46 adjustably mounted in floor-based support 47 by means of nut 48.

Referring to Figs. 1, 3 and 10, a pulley shaft 50 (Fig. 3) extends through hollow trunnion pin 75

39, and has secured to its outer end a pulley 51 and to its inner end a bevel gear 52 which meshes with a bevel gear 53 secured on one end of shaft 54 mounted in bearings 55 and 56 secured to the inner face of stretcher 29. The other end of shaft 54 has secured thereto a sprocket gear 57 through which the cylinder unit, next to be described, may be rotatively driven in whatever degree of tilt it is caused to assume.

10

The cylinder unit

Referring to Figs. 1, 3 and 5, the cylinder unit includes four hollow cylindrical elements or sections 60, 61, 62 and 63, made of perforated sheet metal, or similar material, joined end to end, as best seen in Fig. 5, by rings, like ring 64 joining sections 60 and 61. Ring 64, taken as an example, has laterally extending flanges 65 and 66 (Fig. 5) to which the associated cylindrical sections are bolted, and has an inwardly tapering flange 67 which provides a restricted circular opening 68 (see Fig. 4) or aperture between the two cylindrical sections. Referring to Figs. 4 and 5, the opening 68 is provided with a flanged collar 69a bolted to the side of ring 64 which comprises the end of cylindrical section 60 and flaring inwardly and laterally into cylindrical section 61, leaving the edge of the collar bordering the aperture 68 sharp, to make it easier to cause the beans to transfer from one cylindrical section to the other, as will be explained.

The receiving end of the cylindrical unit is closed by an end piece 69 (Fig. 2) having a central circular aperture 70 from which extends outwardly a barrel-like bean receiving throat 71 (Figs. 1 and 8), the outer end of which is provided with a sprocket gear 72 coupled by chain 73 to sprocket gear 57, whereby the cylindrical unit is rotated. The inner side of end piece 69 is provided with a flanged distributing collar 74 (Fig. 8).

The delivery end of the cylindrical unit is provided with an end wall 75 (Fig. 7) having a central aperture 76 provided with an outwardly projecting and outwardly flaring collar 77 (see also Figs. 1 and 3) through which the snipped beans are delivered onto a sorting table 99.

The ring 78 (Figs. 1, 3 and 13) is provided on its outer periphery with side walls to form a track 79 which rides on rollers 80 and 81 (Fig. 13) journaled on studs held in upwardly extending flange 82 of member 31, to rotatively support the middle of the cylindrical unit. Surrounding the bean receiving barrel-like member 71 (Fig. 1) is a ring 83 having side walls to form a track in which ride rollers 84, 85, 86, 87, 88 and 89 (Fig. 11) journaled on studs extending between flanges 90 and 91 integral with members 32 and 33, to form a roller support and retaining means for the receiving end of the cylindrical unit. At the delivery end of the cylindrical unit is a flanged ring 92 (Figs. 1 and 3) having a circumferential track 93 and an end thrust surface 94. Rollers 95 and 96 (Fig. 7) journaled on studs projecting side-wardly from a vertical flange on member 34 ride in track 93 to rotatively support the delivery end of the cylindrical unit. The thrust surface 94 bears against surface 97 (Fig. 1) of member 34 to hold the cylindrical unit from endwise movement when tilted to the position shown in Fig. 1.

Stretching between the end walls of each section are a number of tumbling rods, like rods 100 and 101 (Fig. 3) in section 61, which operate to tumble and shift the beans as the unit is rotating to

afford them every opportunity to enter the perforations 102 in the drums, shown partially, only, in Fig. 3. These perforations are countersunk from the inside, as shown in Fig. 2, in the manner set out in my patents formerly referred to.

Two shearing knives are provided for each cylindrical section which may be adjusted to be held in resilient shearing contact with the cylindrical surface on the outside, to shear off the ends of beans protruding through the perforations.

Associated with cylindrical sections 60, 61, 62 and 63 are upper knife blades 103, 123, 143 and 163, respectively, and lower knife blades 104, 124, 144 and 164, respectively (Fig. 1).

Each upper blade is mounted like blade 103, associated with cylindrical section 60, which will be described as a typical mounting. Knife blade 103 is pivoted at 105 and 106 to supports 107 and 108 (see also Fig. 2) hinged, respectively, to plates 109 and 110 fastened to the upper edge of stretcher 30. Support 107 is yieldingly retained in detent member 111 associated with support 107, said detent being secured to an arcuate knife bracket 112 associated with and supporting one end of a stretcher member 117 supporting lower knife blades 104 and 124. Spring 113, adjusted by screw 114, holds knife 103 resiliently against the cylindrical surface of section 60 in a manner to shear off the ends of beans as the cylindrical unit rotates in the direction of the arrow (clockwise in Fig. 2). Knife 103 may be swung out of effective position when desired. Knives 123, 143 and 163 are mounted in a like manner.

Two stretcher members 117 and 137 (Fig. 1) are provided, stretcher 117, associated with knives 104 and 124, being held on one end by arcuate member 112 secured to the under side of stretcher 30 (Fig. 2) and being held on the other end in support member 31 (Fig. 13) and stretcher member 137, associated with knives 144 and 164, being supported on one end in support member 31 and supported at the other end by arcuate support member 138 secured to the underside of stretcher 30. Figs. 1 and 2 illustrate how the lower knife blades, knife blade 104 being taken as an example, are mounted. Secured to stretcher 117 are hinge plates 115 and 116 to which the knife blade 104 (Fig. 2) is pivoted and resiliently held against the cylindrical surface of section 60 by an adjustable spring 118. Knife blades 124, 144 and 164 are mounted in a similar manner.

Bean transfer mechanism

As beans are introduced into the bean receiving throat 71 (Fig. 8) they are received into the interior of cylindrical section 60 and by the rotary tumbling action, work their way by gravity toward the apertured wall separating sections 60 and 61 (Figs. 5 and 9) of the cylindrical unit and, if the bean transfer mechanism, now to be described were not provided, they would pile up until they were at a height which would allow them to tumble through the aperture 68 into section 61, where the same action would be repeated. It is undesirable to have such an uncontrolled piling-up of the beans at the lower end of each cylindrical section as it interferes with the efficiency of the machine and may act to injure the beans. Therefore, on the lower end wall of each section, that is, at the right end of each section as seen in Figs. 1, 3, 5 and 9, I provide a plurality of radial paddles, preferably six in number, such as paddles 175, 176, 177, 178, 179 and 180 (Figs. 3 and 6) which are secured in edge and end abutment to a

ring 181 having one flange 182 (Figs. 3 and 6) secured to the flange 182a associated with the ring 78 joining sections 61 and 62, and another flange 183 secured to flange 184 of collar 185.

The detailed structure for the bean transfer mechanism, and its operation, will be explained with reference to Fig. 9, which shows the transfer mechanism between sections 60 and 61, illustrating how the beans are carried by the paddles, during rotation. Paddles 191, 192, 193 and 194 (see also Fig. 5), which comprise a portion of those in section 60, are shown attached to ring 195 secured to flange 65 of ring 64 and to collar 69a, the internal edges, such as edge 196 of paddle 191, coming next to aperture 197. As beans 198 pile up at the lower end of section 60 the paddles, such as paddle 194 carry a portion of them upwardly, as the cylindrical unit rotates, to a point where the slope of the paddle causes them to start dropping off and downwardly, such action being completed by the time the paddle is at the top of its rotational cycle, as is the case with paddle 191. Due to the axial tilt of the cylindrical unit the vertical drop of the falling beans will cause a portion of them 200 nearest the aperture to fall through the aperture into cylindrical section 61, the remainder dropping, of course, back into the pile 198 for another lift, the degree of axial tilt of the unit governing the rate of transfer of the beans from section to section. By this transfer structure the beans may be made to progress through the unit, section by section, at a rate which will insure the proper bean snapping action, according to the kind and grade of beans being treated. As before said, the narrow edge 201 of such apertures, given by the shape of the collar, gives maximum opportunity for the beans to fall into the next lower section.

Multiple unit system and conveyor feeder

Referring to Figs. 14 and 15, I show, diagrammatically, three cylindrical bean snapping units 205, 206 and 207, in parallel arrangement, the receiving ends of each having protruding therewith into the delivery end of a trough slide, like trough slides 208, 209 and 210, which are supplied with beans from an endless conveyor belt 211 moving in the direction of the arrow. The power roller 212, supporting one loop of the belt is driven through a pulley 213 and belt 214 from a motor, not shown. An idler roller not shown, supports the other end of the belt in the usual manner. A framework, comprising legs, stretcher members and cross members, like leg 215, stretcher members, 216 and 217 and cross member 218, support the conveyor belt and standards 219, 220 and 221, to which diverting arms 222, 223 and 224 are hinged. Arms 222, 223 and 224 extend over the top stretch of the conveyor belt in scraping contact therewith, and may be adjustably swung on the associated hinge to extend a certain distance across the belt. Arms 222, 223 and 224 are progressively longer, relatively. As shown, beans deposited in hopper 225 will be carried by hopper unloading belt 226 moving in the direction of the arrow on rollers 227 and 228, driven through belt 229 by power pulley 230, and dropped onto conveyor belt 221, to be carried in the direction of the diverting arms 222, 223 and 224, which each divert an aisle of beans into the associated cylindrical units. An operator by adjusting the arms from time to time can keep a continuous flow of beans entering into the units, at a selected rate for each unit.

Operation

In operation, the various cylindrical units are tilted so the axes of rotation are adjusted to give the best bean snipping operation for the variety and grade of beans being used, and are started rotating after the knives have been adjusted to shearing position. Conveyor belts 211 and 226 then are set in motion and beans are dumped into hopper 225 after the arms 222, and 223 and 224 have been set so that approximately one-third of the conveyed beans is fed to each cylindrical unit. After beans start issuing from the cylindrical units, the tilt of the units is further adjusted, and the arms 222, 223 and 224 are regulated so the treated beans appear snipped in sufficient percentage to meet the requirements of the user. From this point, the operation proceeds automatically as long as beans are dumped into the hopper 225. It is apparent that the speed of belts 226 and 211 may be regulated to produce further adjustment of the rate of feeding of the beans to the snipping units.

By my structure I provide a continuous bean snipping machine which is efficient in use and in the saving of auxiliary labor required for its operation.

I am aware that the device shown herein may be varied considerably without departing from the spirit of my invention and, therefore, I claim my invention broadly, as indicated by the appended claims.

Having thus described my invention, what I claim as new and useful and desire to secure by Letters Patent, is:

1. A bean snipping machine comprising a plurality of cylindrical wall sections, each having a multiplicity of perforations therein; means for securing said sections to each other, end to end, with their axes in longitudinal alignment so that they have a common axis of rotation; transverse partitions disposed between and secured to adjacent sections, each partition having a central opening through which bean pods may feed from the interior of one section to the interior of the next adjacent section; a plurality of radial pad-

dles, secured to each partition at the feed side thereof, extending from the adjacent wall section to points adjacent the central opening in the partition, forming a series of pockets adjacent said partition and surrounding said central opening; a plurality of knives, one supported in engagement with the exterior of each wall section to cut off the ends of pods protruding through said perforations as the wall sections rotate; means for mounting said connected wall sections as a unit with its axis of rotation inclined to the horizontal; and means for rotating said connected wall sections as a unit about said common axis of rotation, whereby pods lodged in the pockets at the discharge end of one wall section will be carried by rotation thereof to a point above the axis inclined to the horizontal and then drop by gravity through the central opening into the interior of the next cylindrical wall section so that bean pods will be fed continuously through said inclined rotating unit from the upper feed end to the lower discharge end thereof.

2. The bean snipping machine of claim 1 in which the central opening in each partition is defined by a sharp edge to prevent pods dropped from said pockets from lodging thereon.

3. The bean snipping machine of claim 1 in which the central opening in each partition is surrounded by an inclined flange on the side thereof opposite said pockets, forming a funnel flaring outwardly into the interior of the next cylindrical wall section.

BENJAMIN I. BUCK.
